FIG. 7

UNITED STATES PATENT OFFICE

1,991,281

APPARATUS FOR BANDING BOXES

Bror Anders Emil Johnson, Alsten, Sweden, assignor to Aktiebolaget Gerh. Arehns Mekaniska Verkstad, Stockholm, Sweden, a joint-stock company of Sweden

Application June 1, 1933, Serial No. 673,924
In Sweden June 17, 1932

13 Claims. (Cl. 216—9)

This invention relates to an apparatus for banding boxes or the like; and has special reference to the provision of a banding apparatus of the type in which a flap of the strip to be used as 5 banding material or both of its flaps are folded primarily against one side of the box and subsequently against an adjacent box side.

In devices heretofore known in the art the medial portion of the strip is held with pressure 10 against one side of the box being at rest and the edge or flap of the strip is folded down against an adjacent side of the box by a folding member which moves along said side past the edge of the strip. Thereupon another folding member is 15 moved to turn the flap up against the bottom side of the box. If however the banding operation is performed rapidly, the flap will be flung outwards when being released from the primary folding member and the secondary folding member will not engage said flap and thus the banding 20 operation is uncompleted. Even though the primary folding member should not be moved past the edge of the flap but is given a movement on a line at right angle to the line of the primary movement immediately upon reaching an edge of the box the strip will not be effectively secured to the box on account of its tendency to be flung out from the side of the box against 25 which it is primarily folded, and on subsequently discharging the banded box from the apparatus the strip is likely to be wrinkled or torn off and an effective sealing will not be obtained.

My present invention contemplates a novel apparatus for banding boxes or the like, such apparatus not being subject to the inconveniences above mentioned.

A main object of my invention is to provide 40 an apparatus for banding boxes or the like in which the strip is folded against a side of the box by a folding member which is moved past an edge of the box but not past the edge of the strip and subsequently moved over said edge to apply the flap to an adjacent box side whilst the strip is held tightly pressed against the box side 45 previously mentioned.

Another object of my invention is to provide 50 an apparatus of this type in which a smoothing or pressing member is conveyed behind the folding member during the primary movement of the latter and is held during the secondary folding operation with pressure against the side of the box against which the strip is primarily folded.

A further object of my invention is to provide 55 an apparatus of the same type in which a pressing

member is moved against the side of the box against which the strip is primarily folded and held with pressure against said side during the second stage of the folding operation.

To the accomplishment of the foregoing and such other objects as may hereinafter appear, my invention consists in the elements and their relation one to the other defined in the claims, reference being had to the accompanying drawings which show preferred embodiments of my invention and in which:

Figures 1 and 2 are front elevational views of the apparatus shown in two different stages of operation.

Figure 3 is a side elevational view of the same. 15

Figures 4—6 are views showing the banding operation in successive stages.

Figure 7 is a side elevational view of part of a modified form of the apparatus. 20

Referring to the drawings the box 1 to be banded is positioned between two roller shaped folding members 2 rotatably journaled on links 3. The links are pivoted to pins 4 on the free ends of arms 8 and actuated each by a coiled tension spring 5. The links are provided with adjusting screws 6 which are forced by the spring against shoulders 7 on the arms 8, thus limiting the upward stroke of the rollers 2. Each arm 8 is pivoted to a crank arm 10 on a pin 9, said crank arm being rigidly connected with another arm 11, arms 10 and 11 thus forming a bell crank lever keyed to a shaft 12. 25

A roller shaped pressing member 13 is arranged adjacent each folding member, said rollers 13 being journaled on pins 14 on the free end of arms 15 which are pivoted on the pins 9. 30

The arms 8 are provided with shoulders 16 engaged by rollers 17 rotatably journaled on a free end on one arm 18 of a bell crank lever rotatably journaled on a shaft 19. The other arm 20 of the bell crank lever is likewise provided with a rotatable roller 21 engaging the periphery of a cam disc 22 under the influence of a coiled tension spring 23 connected to the two arms 8. The two cam discs 22 are keyed to a main drive shaft 24. Continuous rotary movement is imparted to said shaft in any well known manner and therefore no description of the driving means is needed herein. 40

The arms 11 carry rotatable rollers 25 riding on the periphery of cam discs 26 likewise keyed to shaft 24, and are connected by means of a coiled tension spring 29. 45

The position of the arms 8 relative to that of the arms 15 before beginning the folding opera- 50

tion is determined by coiled tension springs 27 tending to move said arms together, thereby causing adjusting screws 28 in the arms 15 to engage the rear side of the arms 8.

5 For holding the medial portion of the strip 31 to be folded under pressure against the upper side of the box a stamp 30 of known structure is used. The means for actuating said stamp is likewise known in the art and therefore description thereof is omitted herein.

10 The modified form of the apparatus is intended for folding but one flap of the strip against two adjacent sides of the box. The roller 13 is omitted and replaced by a stamp 36 on a rod 37.

15 Reciprocating movements are imparted to said rod by a grooved disc 38 keyed to a continuously rotating shaft 39 driven in any well known manner. A pin 40 on the rod engages the groove 41.

20 In the operation of the embodiment of apparatus shown in Figures 1 and 2 the box 1 is conveyed in any well known manner into a position beneath the folding members and a strip 31 of paper or similar thin material is applied to

25 the box likewise in any well known manner for instance by means of a pincher 32, so that its medial portion rests on the upper side of the box as illustrated in Fig. 4. Thereupon the strip is pressed against the box by the stamp 30. At

30 this period the different elements of the banding apparatus occupy the position illustrated in Fig. 1. The arms 8 and 15 are then caused to move downwards maintaining the relative position illustrated in Figs. 1 and 4 under the influence of the rotating cam discs 26 permitting the arms 11 to swing

35 somewhat together under the influence of spring 29, and the rollers 2 fold the flap of the strip down against the vertical sides 33 of the box, until the rollers 2 and 13 occupy about the position illustrated in Fig. 5. On the rapid movement of the rollers the flap of the strip has a

40 tendency to be flung outwards as shown in Fig. 5 but is prevented therefrom by the roller 2, which does not release the flap. The cam discs are

45 timed in such relation that immediately upon the roller 2 having passed the edge 34 of the box, the descending movement is arrested and the arms 20 each enter a curvature on a disc 22, thereby

50 swinging the arms 18 together. Then the arms 8 are free to swing together, so that the rollers 2 fold the flaps of the strip up against the lower side 35 of the box tightly and adhesively applying them to said side, as illustrated in Figures

55 2 and 6. The presser rollers are conveyed on the vertical sides 33 of the box behind the rollers, and hold the strip against said sides with yielding pressure when the second stage of the folding operation, viz. the applying of the flap ends

60 of the strip to the lower side 35 of the box is performed, thus preventing any injurious effect caused by the tendency of the strip to be flung outwardly and not to adhere to the side of the box.

65 As the links 3 are free to yield somewhat downwards, the rollers 2 accommodate themselves automatically to press against the side 35 of the box, even though the vertical position of the side 35 is somewhat varied.

In operating the modified apparatus shown in Figure 7 the stamp 36 is held in a retired position during the descending movement of the roller 2 until it has reached the edge 34 of the box. Then the stamp 36 is moved against the side 33 and holds the strip with pressure against said side during the second stage of the folding operation.

After finishing said operation the stamp is re-tired again.

Although but two specific embodiments of this invention have been herein shown and described, it will be understood that numerous details of the construction shown may be altered or omitted without departing from the spirit of this invention as defined by the following claims.

What I claim as new and desire to secure by Letters Patent of the United States of America 10

15 1. In an apparatus for banding boxes or the like a strip folding member, means for moving said member on a primary box side for folding a flap against said side, means for arresting said movement immediately upon the folding member having moved past an edge of the box and for shifting said member to move on an adjacent secondary box side to fold the remaining portion of the flap against said adjacent side, and means 20 for holding the strip with pressure against the primary box side during the second stage of the folding operation.

2. In an apparatus for banding boxes or the like a strip folding member, means for moving said member on a primary box side for folding a flap against said side, means for arresting said movement immediately upon the folding member having moved past an edge of the box and for shifting said member to move on an adjacent 25 secondary box side to fold the remaining portion of the flap against said adjacent side, a pressing member, and means for moving said member behind the folding member and holding it during the second stage of the folding operation with 30 pressure against the portion of the strip having been applied to the primary side of the box.

3. In an apparatus for banding boxes or the like a strip folding member, means for moving said member on a primary box side for folding a flap against said side, means for arresting said movement immediately upon the folding member having moved past an edge of the box and for shifting said member to move on an adjacent secondary box side to fold the remaining portion of the flap against said adjacent side, a pressing member, and means for moving said member behind the folding member, arresting its movement immediately before having reached an edge of the box, and holding it during the second 45 stage of the folding operation with pressure against the portion of strip having been applied to the primary side of the box.

4. In an apparatus for banding boxes or the like a strip folding member, means for moving said member on a primary box side for folding a flap against said side, means for arresting said movement immediately upon the folding member having moved past an edge of the box and shifting said member to move on an adjacent secondary box side to fold the remaining portion of the flap against said adjacent side, a pressing member, and means for moving said member against the primary box side and holding it during the second stage of the folding operation with 50 pressure against the portion of the strip having been applied to the primary side of the box.

5. In an apparatus for banding boxes or the like a reciprocating member for folding a flap of a strip against two adjacent sides of the box, a 55 cooperating reciprocating pressing member for holding with pressure the flap against one of said sides of the box, means for moving the folding member on two different substantially rectangular lines, and means for moving the pressing 60

member on one of the two travelling lines of the folding member.

6. In an apparatus for banding boxes or the like a pair of reciprocating cooperating members, each for folding a flap of a strip against two adjacent sides of a box, a pair of reciprocating pressing members cooperating with the folding members and adapted to hold with pressure the flap against one of said sides of the box, means for moving each folding member on two different and substantially rectangular lines, and means for moving each pressing member on one of the travelling lines of a corresponding folding member.

15 7. In an apparatus for banding boxes or the
like a yieldingly connected pair of reciprocating
cooperating members each for folding a flap of a
strip against two adjacent sides of a box, a pair
of reciprocating pressing members cooperating
with the folding members and adapted to hold
20 with pressure the flap against one of said sides
of the box, means for moving each folding mem-
ber on two different and substantially rectangu-
lar lines, and means for moving each pressing
25 member on one of the travelling lines of a corre-
sponding folding member.

30 8. In an apparatus for banding boxes or the like a pair of reciprocating cooperating members each for folding a flap of a strip against two adjacent sides of a box, a yieldingly connected pair of reciprocating pressing members cooperating with the folding members and adapted to hold with pressure the flap against one of said sides of the box, means for moving each folding member on two different and substantially rectangular lines, and means for moving each pressing member on one of the travelling lines of a corresponding folding member.

9. In an apparatus for banding boxes or the
40 like a roller shaped reciprocating member for
folding a flap against two adjacent sides of the
box, a cooperating reciprocating roller shaped
pressing member for holding with pressure the
flap against one of said sides of the box, means
45 for moving the folding member on two different
substantially rectangular lines, and means for
moving the pressing member on one of the travel-
ling lines of the folding member.

10. In an apparatus for banding boxes or the like a roller shaped reciprocating member for folding a flap against two adjacent sides of the box, a yielding link carrying said folding member, a cooperating reciprocating roller shaped pressing member for holding with pressure the flap against one of said sides of the box, means for moving the folding member on two different substantially rectangular lines, and means for moving the pressing member on one of the travelling lines of the folding member.

11. In an apparatus for banding boxes or the like a roller shaped reciprocating member for folding a flap against two adjacent sides of the box, a swinging arm, a link yieldingly pivoted to said arm and carrying the folding member, a cooperating reciprocating roller shaped pressing member for holding with pressure the flap against one of said sides of the box, means for moving the folding member on two different substantially rectangular lines, and means for moving the pressing member on one of the travelling lines of the folding member.

12. In an apparatus for banding boxes or the like a strip folding member, means for moving said member on a primary box side for folding a flap against said side, means for arresting said movement immediately upon the folding member having moved past an edge of the box and for shifting said member to move on an adjacent secondary box side to fold the remaining portion of the flap against said secondary side, means for holding the strip with pressure against the primary box side during the second stage of the folding operation, and a member for holding the strip with pressure against a box side opposite to said secondary box side. 11

13. In an apparatus for banding boxes or the like, a reciprocating member for folding a flap of a strip against two adjacent sides of the box, a cooperating pressing member for holding the flap with pressure against one of said sides of the box, means for imparting to said folding member folding movement along one of said sides of the box, and means for simultaneously forcing said pressing member against the other side of the box. 45

BROR ANDERS EMIL JOHNSON.
